UNITED STATES PATENT OFFICE

ARGYLE CAMPBELL, OF CHICAGO, ILLINOIS, ASSIGNOR TO ENTERPRISE RAILWAY EQUIPMENT COMPANY, OF CHICAGO, ILLINOIS, A CORPORATION OF ILLINOIS

CAR DOOR

Application filed April 21, 1928. Serial No. 271,727.

My invention relates to improvements in car doors and especially that type slidably mounted with respect to a door opening.

My invention particularly relates to improved reinforced metal doors adapted for box and automobile cars, such doors being usually mounted on rollers and supported at the top or bottom thereof and are generally maintained against outward movement by means of top and bottom guides supplemented by interlocking connections at the vertical margins of said doors when the latter are in operative position over a door opening. In doors of this character and supported as above described, there is a considerable distance intermediate the supporting margins, and this body portion is liable to sag or buckle unless adequately reinforced and the strains properly distributed with reference to the margins of the door. It is also essential that such doors in addition to being of great strength should also be light in weight.

It is an object of my invention to provide a door which will have strong marginal reinforcements and have the body portion intermediate the margins adequately rigidified against buckling along vertical, horizontal and diagonal cross lines and still be light in weight and relatively cheap to manufacture.

It is also an object of my invention to provide a car door of such construction as will permit of reinforcement by a central rigidifying embossment defining an intelligible indicatory symbol whereby the door will possess advertising value in addition to being of great strength, and to further provide a construction which will cooperate with the said main embossment to rigidify the body of the plate on various crosslines and transmit the bending strains from the said central embossment to the margins of the door in an efficient manner.

Other and further objects of my inven-

tion will more clearly appear from the description and claims hereinafter following.

In the drawings forming a part of this specification, Figure 1 is a front elevational view of a freight car door embodying my 50 improvements.

Figure 2 is a vertical sectional view taken through the door on a line corresponding substantially to the line 2—2 of Figure 1.

Figure 3 is an enlarged horizontal sectional view taken through the door and on a line corresponding substantially to the line 3—3 of Figure 1, intermediate parts being broken away to better accommodate the view on the sheet.

Figure 4 is a lower sectional view of the door on an enlarged scale, said view corresponding substantially to line 4—4 of Figure 1.

Figure 5 is a front elevational view of a car of similar construction to that shown in Figure 1 but showing a modified form of construction to accommodate an embossed symbol indicative of a different railroad system.

Figure 6 is a vertical sectional view taken thru the door and on a line corresponding substantially to line 6—6 of Figure 5.

Figure 7 is a front elevational view of a door incorporating a different embossed symbol and the door construction modified to suit the same.

Figure 8 is a vertical sectional view taken through the door and on a line corresponding substantially to line 8—8 of Figure 7.

Figure 9 is a front elevational view of a car door showing still another modification.

Figure 10 is a vertical transverse sectional view taken through the door shown in Figure 9 and on a line corresponding substantially to line 10—10 of the same.

Figure 11 is a front elevational view of still another modification.

Figure 12 is a vertical sectional view taken through the door shown in Figure 11.

and on a line corresponding substantially to the line 12—12 of Figure 11.

In said drawings the improved door is indicated at A and the usual front and rear door posts defining a door opening of a box car are indicated at 10 and 11 respectively, said door posts being preferably of Z-form presenting outer flanges of extended width disposed in a plane parallel to the car door 10 and adjacent thereto when said car door is in operative position over the door opening.

A wooden filler block 12 is associated with each Z bar post to which the usual wooden sheathing 13 of the car is secured. On the 15 rear door post and substantially in alignment with the front face thereof, there is disposed an angularly shaped sealing member 14 adapted to cooperate with the rear edge of the door, and on the front door post 20 there is disposed a sealing member 15 adapted to cooperate with the front vertical margin of the door to form a sealing joint. The member 15 preferably consists of an angularly shaped rolled member having the outstanding flange indicated by dotted lines in Figure 3 deflected inwardly towards the door as indicated at 16 and forming a flared overlapping flange for the door.

30 The improved door which is generally indicated by the reference character A includes a marginal rectangular frame which includes a top horizontally extending member 17 and front and rear marginal members as indicated at 18 and 19 respectively, the said marginal members 17, 18 and 19 being preferably formed of Z-shaped rolled sections with flanges 20, 21 and 22 of the respective marginal members disposed substantially in the outer plane of the door and the intermediate webs thereof projecting inwardly of the outer plane and substantially at right angles to the main plane of the door and defining substantially the depth 45 of the door. The respective marginal members 18 and 19 are connected to the top member 17 by gussets 23—23 and the corners of the door are welded for the purpose of attaining weatherproof joints.

50 The body of the door A intermediate the said framing members 17, 18 and 19 is preferably formed of upper and lower metallic panels as indicated at 24 and 25 respectively and said panels are preferably 55 united to each other along a horizontal line by rivets as indicated at 26. The panel 24 is disposed in the upper portion of the door and is secured at its edges flatwise to the inwardly projecting flanges 20, 21 and 22 60 of the respective marginal members 17, 18 and 19.

The lower panel 25 of the door is rigidified at its lower margin by bending the lower portion of said panel inwardly as indicated at 27 and thereafter downwardly as

indicated at 28, thereby presenting a Z-shaped lower margin with the depending flange 28 disposed in substantially the inner plane of the door. Said panel 25 is preferably formed of metal relatively thicker than the upper panel 24, which serves to maintain the frame against racking and warping and forms a lower margin of great strength, and protects the lower portion of the door against injury, due to shifting loads in the car. The edges of the lower panel are secured flatwise to the inwardly projecting flanges 21 and 22 of the respective vertical margins 18 and 19. Secured to the said depending flange 28 of the lower panel 25 on the inner side of the door is a flat facing plate 29 which extends above the lower margin of the door for an appreciable distance and provides a smooth and even surface for contacting with the car structure as the door is moved across the door opening.

On the inner side of the door and between the plate 29 and the inner face of the panel 25 are diagonally extending metallic members 30—30. Said members are preferably of U-shape with connecting flanges 130—130 and each extends across the plane of the respective upper and lower panels diagonally from the lower margin of the door to the respective vertical margins, said flanges 130—130 being united to the respective panels by rivets 31. The said braces are thus so disposed as to extend to the lower margin of the door and the vertical margins intermediate the ends thereof and cooperate to resist bending of the door on vertical lines and also counteract racking and warping tendencies of the door. The braces are also united to the face plate 29 by rivets 32. Intermediate the face plate 29 and inner face of the panel 25 there are disposed wooden fillers 33 and 34 which operate to effectively space the face plate, strengthen the lower margin of the door and prevent the entry of moisture or other undesirable matter between the face plate and panel of the door.

The upper panel 24 is rigidified intermediate the diagonal bracing and upper and side marginal reinforcement members by having embossed therein an integral embossment defining a railroad monogram. Said monogram, in the present embodiment, includes a rectangularly shaped embossment having the outline 36 disposed at an angle with reference to the vertical and horizontal margins of the door and within the confines of said outline the plate is rigidified by embossed lettering 37, which is indicative of the name of a railroad system.

The arrangement of the embossment in relation to the door bracing as presented by the vertical margins and diagonal braces permits of reinforcement of the plate clear

across the door from one vertical margin to the other and inasmuch as the said embossment is extended vertically for a considerable distance in the plane of the diagonal members and above the same, it will be evident that the diagonal members co-operate with the embossment for providing continuity of reinforcement between the margins of the door and the door bracing members. For the purpose of further strengthening the corners of the door and co-ordinating the rigidifying effect of the central embossment with the marginal reinforcements and diagonal braces there are provided supplemental embossments 38 and 39 respectively, above and below the said intelligence conveying main embossment, said embossments which are preferably merely corrugations of meaningless character, extend substantially from side to side of the door and parallel with the horizontal margins of the panel, and are deflected at right angles thereto adjacent the vertical margins and extended in the plane of the main embossment thus straddling the same. The upper embossment 38 has the horizontal section indicated at 40 and the respective vertical sections indicated at 41—41, and the lower of said embossments 39 has the horizontal section indicated at 42 and the vertical portions at 43—43. The vertical sections of the respective upper and lower embossments 38 and 39 extend in the plane of the main embossment and in combination with their horizontal portions enframe the main embossment at the corners of the panel and thus in addition to cooperating with the margins of the door and the main embossment to prevent bending of the door along horizontal and vertical axes, also operates to prevent bending along diagonal lines. The said horizontal and vertical sections of the lower embossment as indicated at 42 and 43 are respectively so disposed as to intersect the diagonal members 30 on horizontal and vertical lines, the panel 24 being riveted to the said diagonal members on each side of and in the angle formed by said angularly related portions 42 and 43. The lower panel 25 is reinforced with a plurality of corrugations 44, said corrugations being disposed to extend across the plane of the diagonal members 30—30 whereby said corrugations operate to support the door panel beyond the diagonal members and thus strengthen the door against bending on diagonal lines. The said embossments 44 are formed to extend outwardly of the plate in the opposite direction to the U-shaped portion of the braces 30 thus providing for great strength on intersecting crosslines.

At the rear edge of the door the inner flange of the Z-shaped vertical margin 19 is bent rearwardly in the form of a U as

indicated at 45 which embraces the angle shaped member 14, and at the front edge of the door the inner flange 46 of the vertical marginal Z-shape member 18 is adapted to extend within the flared opening 70 formed by flange 16 of member 15 in cooperation with the door post 10.

In the construction shown in Figures 5 and 6, the general framework and construction of the door as well as the lower panel 75 are of the same general formation as that described in connection with Figures 1 to 4 inclusive, except as to the main central rigidifying embossment in the upper panel 80 of the door, which is indicative of a different railroad system, and the construction of the door is modified to suit said embossment. In said Figures 5 and 6, 200 indicates the upper horizontal margins, 201 and 202 the front and rear margins respectively, 203 the upper panel, 204 the lower panel, 205 the diagonal braces, 206 inner facing plate, 207 and 208 the filler blocks and 209 the corner gussets. The lower panel 204 is rigidified by two horizontally extending 90 embossments 210 and in the upper panel 95 there is a central intelligence conveying embossment having a substantially circular outline 211 formed with a diamond-shaped portion 212 projecting beyond the ends of said circular section, said projecting portion of the diamond-shaped portion being adapted to bridge as a beam the space intermediate the circular outline 211 and the adjacent vertical margin, it being noted that in the particular embodiment shown the circular outline 211 is spaced appreciably from the vertical margins and also from the lower margin of the panel and the respective diagonal members 205—205.

The said main embossment is enframed above and below the diamond-shaped portion within supplemental upper and lower embossments indicated at 213 and 214 respectively. Said upper embossment 213 includes a horizontally extending corrugation disposed intermediate the top margin of the door and the main embossment and adjacent each vertical margin of the door. Said embossment is deflected downwardly to present vertical sections 215—215, said sections being extended along a vertical line into the plane of the main embossment. The lower of said supplemental embossments indicated at 214 includes a horizontally extending embossment extending across the plane of the diagonal braces 205—205, and adjacent the vertical margins of the door. Said embossment is formed with sections 216—216 which extend upwardly into the plane of the main embossment and intersect the diagonal members on vertical lines.

In the modification shown in Figures 7 and 8, 300 indicates the upper horizontal margin of the door, 301 and 302 the front

and rear margins of the door respectively, 303 the upper panel, 304 the lower panel, 305—305 the diagonal braces, 306 the inner face plate, 307 and 308 filler blocks and 309 corner gussets.

The lower panel 304 is rigidified by two horizontally extending embossments 310 which extend across the plane of the diagonal members. The upper panel 303 is rigidified by a central embossment of generally circular outline as indicated at 311, said outline being preferably of a size to extend immediately adjacent the diagonal braces 305—305. Adjacent its central portion the main embossment includes an outwardly extending body portion 312 which extends substantially from side to side of the door and is extended on one side into the plane of one of the diagonal braces 305 and on the opposite side terminates adjacent the other diagonal brace thereby providing a beam of rigid construction extending between the respective vertical margins of the door. Above this central embossment there is disposed an enframing embossment 313 which extends horizontally across the door and is formed with vertically extending portions 314—314 extending parallel with the vertical margins of the door and in the plane of the central embossment for the respective sides thereof. At the lower margin of the upper panel there is formed a horizontally extending corrugation 315 which extends across the plane of the diagonal members.

In the modification shown in Figures 9 and 10, the numeral 400 indicates the upper horizontal margin, 401 and 402 the front and rear vertical margins respectively, 403 the upper panel, 404 the lower panel, 405—405 the diagonal braces, 406 the inner face plate, 407 and 408 filler blocks and 409 corner gussets. The lower panel is rigidified by two horizontally extending embossments 410 and in the upper panel there is a central embossment 411 which is formed of substantially circular outline tangent to the horizontal and vertical margins and also to the diagonal braces. Surrounding said central embossment there is a continuous embossment 412 which includes horizontally extending portions 413—413 and vertically extending portions 414—414, said horizontal and vertical portions extending across the planes of the diagonal members in horizontal and vertical directions respectively.

In the modification shown in Figures 11 and 12, 500 indicates the upper horizontal margin, 501 and 502 the front and rear vertical margins respectively, 503 the upper panel, 504 the lower panel, 505—505 the diagonal braces, 506 the inner face plate, 507 and 508 filler blocks and 509 the corner gussets. The lower panel is rigidified by two horizontally extending embossments 510 and in the upper panel there is a central rigidifi-

fying embossment of substantially rectangular shape 511 extending substantially from side to side of the door and intermediate the said outline the panel is rigidified by embossed lettering 512, said outline 511 and associated lettering 512 defining a railroad monogram. Above and below the said symbol there are rigidifying meaningless embossments 513—513 of curved shape, said last named being united with the intelligence conveying symbol by depressed portions 514 which serve to give continuity of reinforcement and yet maintain the appearance of a break between said intelligence-conveying embossment and the meaningless embossment.

Above the monogram and associated with the upper circular portion, there is disposed a supplemental embossment 515 extending horizontally from side to side of the door and formed, adjacent its ends, with downwardly extending vertical portions 516—516 which extend into the plane of the central embossment as defined by sections 511, 512 and 513. Adjacent the lower margin of said upper panel there is a horizontally extending corrugation 517 which extends above the plane of the diagonal braces.

While I have herein shown and described what I now consider the preferred manner of carrying out my invention, the same is merely illustrative and I contemplate all changes and modifications that come within the scope of the claims appended hereto.

I claim:

1. In a sliding car door, the combination with a marginal framework including horizontal and vertical marginal members of appreciable depth, said members having flanges lying in substantially the outer plane of the door; of a body plate formed of upper and lower panels secured to said outer flanges, the lower of said panels being bent inwardly from the outer plane of the door and thence downwardly to present a depending flange in the inner plane of the door thereby forming a Z-shaped lower margin for the door; a facing plate secured to said depending flange on the inner plane of the door; diagonally extending metallic members extending from said lower margin to the said vertical margins, said members being of approximately the same depth as the frame and disposed intermediate the planes of said facing plate and said body plate and secured to said facing plate and body plate; and embossments in the body of the plate intersecting said diagonal members and extending into the corner portions of said body plate and cooperating with said diagonal members to prevent bending of the body plate on various crosslines.

2. In a door of the character described, the combination with a marginal framework having upper and lower horizontal members

and vertical side members, all of appreciable depth; of metallic covering for said door, extending across said frame in the outer plane thereof, said covering being provided with a series of rigidifying embossments extending across the door and terminating short of the vertical members; and independent reinforcing means on the inner side of the door and confined within the depth thereof, said reinforcing means lying across the rigidifying embossments and having portions extended beyond the ends of said embossments and secured to the vertical marginal members whereby said reinforcing means operate to bridge as beams the intervening space between the ends of the embossments and the respective vertical marginal members.

3. In a car door of the character described, the combination with a marginal framework having upper and lower horizontal members and vertical side members, all of appreciable depth; of metallic covering for said door extending across said frame in the outer plane thereof, said covering being provided with a series of rigidifying embossments disposed outwardly of the framework and extending across the door and terminating short of the vertical members; and independent reinforcing members at the inner side of the door and confined within the depth thereof, said reinforcing members intersecting the embossments and secured to the covering intermediate said embossments, said reinforcing members diverging towards the vertical members and secured thereto whereby said reinforcing members operate to bridge as beams the space intermediate the ends of the embossments and the vertical members to thereby provide continuity of reinforcement between the respective vertical margins of the door.

4. In a sliding car door, the combination with a marginal framework including upper horizontal and vertical marginal members of appreciable depth, said members having flanges lying in substantially the outer plane of the door; of a body plate formed of a plurality of panels secured to said outer flanges, the lower of said panels being bent inwardly from the outer plane of the door and thence downwardly to present a depending flange in the inner plane of the door thereby forming a Z-shaped lower margin for the door; a facing plate secured to said depending flange of the door and cooperating with the main body covering of the door to form a lower horizontally extending beam; diagonally extending metallic members spaced at their lower ends and extending from said lower beam member to the said vertical margins, said members being of approximately the same depth as the frame and secured at their upper ends to said vertical marginal members; and trans-

verse embossments in said body plate intermediate said lower beam and the upper ends of said diagonal members and intersecting said diagonal members, said embossments extending into the corner portions between the diagonal members and the vertical marginal members for reinforcing said corner portions.

In witness that I claim the foregoing I have hereunto subscribed my name this 19th day of April, 1928.
